Patented Sept. 10, 1974

232,731

BROADHEAD FOR HUNTING ARROW

Anthony L. Altier, Honesdale, Pa., assignor to Indian
Industries, Inc., Evansville, Ind.

Filed July 20, 1972, Ser. No. 273,452

Term of patent 14 years

Int. Cl. D22—05

U.S. Cl. D22—12

Fig. 1

Fig. 2

Fig. 3

Fig. 4

Fig. 5

FIG. 1 is a front perspective of my new design for a broadhead for a hunting arrow;

FIG. 2 is a top plan view of the broadhead;

FIG. 3 is a side elevation;

FIG. 4 is a rear elevation; and

FIG. 5 is a front elevation of the broadhead.

I claim:

The ornamental design for a broadhead for hunting arrow, as shown.
